UNITED STATES PATENT OFFICE

1,976,449

SEAT OR CHAIR WITH ONE SUPPORT

Anton Lorenz, Berlin, Germany

Application May 7, 1932, Serial No. 609,943
In Germany May 7, 1931

2 Claims. (Cl. 155—50)

This invention relates to chairs substantially constructed from steel tubes. The object of the invention is to provide a chair which may be manufactured more cheaply than the steel chairs hitherto used. For this purpose a single resilient metallic tube beginning with a bow is made to extend upwardly from a suitable base, then the tube is bent to a horizontal portion to which a seat is attached, and finally the tube is bent to an inclined portion to which a back is attached. The seat and the back may be connected with the resilient tube in any well known manner, for instance, by means of clamps or supporting arms or the like.

16 The base is preferably formed by the resilient tube itself the lower end of which is bent for this purpose in a plane to a rectangular or circular shape.

20 The invention is illustrated by the annexed drawing of which

Figures 1 and 2 show, a front and side view respectively a chair constructed according to the present invention and

25 Figures 3 and 4 are similar views of a modified form of the chair.

The same reference letters are used for the corresponding parts throughout the figures.

In Figs. 1 and 2 the lower end *a*, *a* of a resilient tube, made, for instance, of steel is bent to a rectangular shape. Then it extends from the forepart of the rectangle, beginning with a bow, upwardly in an inclined direction, forming a straight portion *b*, whereupon it is bent to a horizontal portion to which the seat *c* is attached, and finally the tube is bent to an inclined por-

tion to which the back *d* is attached. The fastening means are not shown as they are common in the art.

In the modification shown in Figs. 3 and 4 the lower end of the tube *a*, *a* is bent in a plane to a loop or circle and rises from the back forming an S-shaped bow *b*.

When constructing a chair according to the present invention less tubular material and bends are required than for the usual type of steel chairs. A further advantage lies in the fact that the awkward lateral supports are omitted, thus making a freer movement of the feet of the person using said seat or chair possible. These frames can moreover be very compactly packed for transport.

I claim:—

1. A chair comprising a resilient tube one end of which is bent in a plane to form a base, the other end of said tube extending upwardly in 75 form of a bow to form a single upwardly directed leg portion whereupon it is bent to a horizontal and finally to an inclined portion, a seat attached to the said horizontal portion and a back attached to the inclined portion of the tube.

2. A resilient chair comprising a single continuous tube, said tube bent to form a flat horizontal base support and extending upwardly from said base as a single upwardly directed stem bent to form a horizontal portion above said base and terminating in an upwardly inclined portion, a seat attached to the horizontal portion of the tube, and a back attached to the inclined portion of the tube.
